UNITED STATES PATENT OFFICE

EDWARD T. WATERS, OF OMAHA, NEBRASKA

ADJUSTING-ROD LOCKING MEANS

Application filed August 13, 1928. Serial No. 299,289.

My invention relates broadly to devices for locking a longitudinally movable member accurately in any of a series of adjusted positions relative to a fixed member, the several 5 positions differing by uniform multiples of length. More particularly my invention relates to the locking of a transversely notched or grooved longitudinally movable rod in a series of positions differing according to the 10 pitch or spacing of the grooves, and in other positions respectively intermediate the positions of the first-mentioned series. My invention is especially adapted and intended for use in connection with integral-line type-casting machines, for locking the adjusting-rod of the movable vise-jaw in adjusted positions, to adapt the vise for receiving groups of matrices of definite line-lengths and no others. A specific object of my invention is 15 to provide a simple, durable and efficient vise-jaw adjusting-rod lock for type-casting machines of the class described, the locking device being so constructed that it may be readily substituted for the devices now in common use on such machines. A further object 20 is to provide convenient and accessible actuating means for the locking member, said actuating means being adapted for indicating to the operator whether the member is in locking or release position, and, when in locking position, indicating also in which series of positions the adjusting-rod is held. More particular objects of my invention will appear hereinafter.

In the accompanying drawings Fig. 1 is a perspective rear view showing a portion of the vise of a type-casting machine, and the vise-jaw adjusting means and locking means therefor embodying my invention; Fig. 2 is a detail fragmentary front view of the lock-actuating means, with the crank-handle removed; Fig. 3 is a detail vertical section on the line 3--3 of Fig. 2; Fig. 4 is a front view of the locking device and portions of the adjusting-rod; Fig. 5 is a side view of the same; Fig. 6 is a rear view of the same; Fig. 7 is a front view of the locking device with the lower portion thereof broken away at the vertical plane of the 45 adjusting-rod axis; Fig. 8 is a side view

of the device, partially in vertical section on the line 8--8 of Fig. 7; Fig. 9 is a view similar to Fig. 7 but showing the locking-pin in a second locking position, and Fig. 10 is a detail transverse section on the line 55 10--10 of Fig. 2.

In Fig. 1 of the drawings the locking device embodying my invention is shown as applied to a type-casting machine of the well-known Mergenthaler structure, the figure being a perspective view showing the rearward side of the upper left-hand portion of the vise. Included in the operative environment of my locking device, as represented in said Fig. 1, are portions of the vise-frame 10, the left-hand vise-jaw 11, first-elevator slide 12, vise-locking screw 13, the vise-jaw adjusting-bar 14, the vise-jaw adjusting-bar link 15, the vise-jaw wedge-bracket 16, the vise-jaw wedge 17, the vise-jaw wedge spring 18, and vise-jaw wedge-adjusting bushing 19, all of which will be understood to be of the usual and well-known structure and mode of operation. In applying my invention to the foregoing structure I provide a vise-jaw adjusting rod 20, vise-jaw wedge-block 21, and vise-jaw adjusting-rod locking-pin 22, which are substituted for the corresponding parts of the ordinary structure. The substitution of the parts is effected by disconnecting the adjusting-rod from the link 15, withdrawing said rod from the bushing 19 and the wedge-block, lifting out the wedge-block and locking-pin, and then assembling in like manner the parts 20, 21 and 22 provided by my invention.

In the operation of type-casting machines of this class, the integral lines or type-slugs are cast in lengths varying by half-picas, and by reason thereof it is desirable that the adjustments of the vise-jaw should be made in the same units of lengths, so as to adapt the vise for receiving groups of matrices of such lengths and no others. The vise-jaw adjusting-rod, therefore, is usually provided with circumferential grooves or notches of which the pitch or longitudinal spacing is one-half a pica ($\frac{1}{12}$ th inch), so that the width of the interengaged teeth or ridges of the adjusting-rod and locking-pin cannot be greater than one-half of such pitch, or $\frac{1}{24}$ th of an inch.

In the usual structure, also, the locking-pin is held in engagement with the adjusting-rod merely by spring-pressure, so that after a period of use, when some wear of the inter-engaged teeth has occurred, or if the notches and teeth of the parts become slightly fouled with dust, grease or the like, the locking-pin may yield and allow longitudinal slippage of the adjusting-rod. Furthermore, because of the small pitch of the notches and teeth of the adjusting-rod and locking-pin, the operator is quite apt to err in setting the adjusting-rod, or may leave said rod at an intermediate position, with the teeth of the locking-pin resting upon the teeth or ridges of the rod, instead of being properly engaged in the notches of the rod, whereby slippage of the rod to an improper adjustment is permitted. The foregoing objectionable features and difficulties of operation of the usual locking device for the vise-jaw adjusting-rod, are avoided by the use of my improved locking device and the actuating and indicating means therefor.

The adjusting-rod 20 provided in the illustrated embodiment of my invention has a plurality of rectangular circumferential grooves uniformly spaced longitudinally, and forming between them rectangular annular ridges or teeth 20', preferably of substantially the same width as the intervening grooves. Said adjusting-rod differs from the ordinary adjusting-rod, in that the pitch or longitudinal spacing of the teeth and grooves is twice as great as in the ordinary rod, said pitch being one pica ($\frac{1}{6}$ th inch) instead of one-half pica ($\frac{1}{12}$ th inch). The wedge-block has a horizontal cylindrical opening for receiving slidably the adjusting-rod, and a vertical rectangular opening for receiving slidably the locking-pin 22, which is rectangular in horizontal section and extends entirely through the wedge-block. In the lower portion of the locking-pin is a vertically elongated transverse opening, through which the adjusting-rod extends. At the upper end of said transverse opening a plurality of semiannular ridges or teeth 24 are provided, the same being proportioned to intermesh with the ridges or teeth 20' of the adjusting-rod when the locking-pin is in the lowered position shown in Fig. 7; and at the lower end of the transverse opening a similar series of ridges or teeth 25 are provided, the same being adapted to intermesh with the adjusting-rod teeth 20' when the locking-pin is in the raised position shown in Fig. 9. At the intermediate position of the locking-pin shown in Fig. 8, both series of the teeth 24 and 25 are disengaged from the adjusting-rod and the latter may be freely moved longitudinally to adjusted positions. The teeth 24 and 25 are offset or interspaced longitudinally of the adjusting-rod axis, so that the teeth 25 are respectively opposite the grooves intermediate the teeth

24. In consequence thereof, the rod may be locked by the engagement therewith of the teeth 24, in a series of positions differing according to the pitch of the teeth 20' on the rod, or at intervals of one pica; and similarly, by interengagement of the teeth 25 with the teeth 20' on the rod, the latter may be locked in any of a series of positions differing by one pica each; but the second series of adjusted positions of the rod are respectively intermediate those of the first series, differing therefrom by one-half pica.

The portion of the wedge-block in front of the locking-pin, adjoining the vise-frame, is formed by a plate 26 which is fixedly secured to the body of the block by screws 27. The plate 26 is extended upwardly so as to project above the upper edge of the vise-frame, as shown in Fig. 1, and in said projecting portion of the plate a shouldered cylindrical opening is formed, in which the crank-disk 28 is disposed revolvably, said crank-disk being shouldered to correspond with the form of the opening, and being insertable therein from the rear side of the plate 26, as best shown in Fig. 10. To the front end of the crank-disk the handle 29 is secured removably by means of the screws 30, the hub portion of the handle being of larger diameter than the front end of the crank-disk, whereby to extend over the face of the plate 26 and retain the disk therein. Stop-pins 31, projecting from the face of the plate 26 as shown, limit rotation of the handle to slightly more than half of a complete revolution. The front end of the crank-disk has therein a diametrically extending rectangular slot 32 in one end of which is slidably disposed the block 33. The crank-pin 34 is formed integrally with said block 33 and extends through a short slot 35 in the rear portion of the disk 28. A roller 36 is mounted revolvably upon the portion of the crank-pin which projects from the rear end of the crank-disk, and said roller fits within a horizontal rectangular groove 37 formed in the front side of the locking-pin 22, near the upper end thereof, the arrangement being such that by rotation of the crank-disk the locking-pin may be moved vertically from and to the locking positions thereof shown in Figs. 7 and 9. In the slot 32 of the crank-disk, adjoining the end of the block 33, are arranged a pair of coil springs 38 of which the ends rest upon pins 39 projecting into the slot 32 at the end thereof opposite the crank-pin, as shown in Figs. 2 and 3. By the pressure of said springs upon the block 33 the end of the block is held normally in frictional engagement with the side of the opening in the plate 26, and serves as a brake tending to hold the crank-disk in any position to which it is turned. Also, by yielding of the springs 38, the block 33 is movable to slightly reduce the throw or radius of movement of the crank-pin, which is

normally slightly greater than is required for actuating the locking-pin between the extreme positions thereof indicated in Figs. 7 and 9. The arrangement is such that when the handle 29 is turned to the vertical position shown in Fig. 8, the crank-pin holds the locking-pin in the intermediate position at which free longitudinal movement of the adjusting-rod is permitted, and by turning the handle from said vertical position to contact with either of the stop-pins 31 the crank-pin is moved slightly past its upper or lower dead-center, as the case may be. Upon approaching the dead-center positions of the crank-pin, however, further movement of the locking-pin is prevented by its engagement with the adjusting-rod, so that the completion of the movement of the handle and crank-disk is permitted only by the yielding of the springs 38 to reduce the throw of the crank-pin to equality with the travel of the locking-pin. After the crank-pin passes the dead-center positions, the springs 38 expand and force the block 33 again to the outer position, thereby tending to hold the handle 29 down against the respective stop-pin with which it is engaged, and thus requiring that the handle be actuated with sufficient force to overcome the resistance of the springs 38 to inward movement of the crank-pin-block 33, in effecting displacement of the parts from their locking positions.

It will be seen that when the crank-pin is in the described locking positions thereof it cannot be displaced therefrom by vertical pressure upon or from the locking-pin. For example, when the locking-pin is in the position shown in Fig. 7, upward pressure thereon tending to release or disengage the same from the adjusting-rod, will merely press the crank-handle 29 down more firmly against the stop-pin 31 with which it is engaged; and a similar effect will be produced by downward pressure upon the locking-pin when the same is in the raised position shown in Fig. 9. Thus the adjusting-rod can be released only by intentional action of the operator, consisting in turning the handle 29 to the raised or releasing position thereof; and accidental releasing of the adjusting-rod, by reason of longitudinal pressure thereon actuating the locking-pin to release position, is effectively prevented.

The position of the crank-handle 29 serves to indicate to the operator whether the locking-pin is in releasing or in locking position, and also, if in locking position, the handle will show in which of the two series of adjustments the adjusting-rod 20 is held. The latter indication results from the relative interspacing of the teeth 24 and 25 longitudinally of the adjusting-rod by an amount equal to one-half the pitch of the teeth; so that if, when the handle is at the right-hand locking position shown in Fig. 9, it indicates

that the adjusting-rod is locked in position for the casting of lines which are some number of full picas in length, then when the handle is in the left-hand locking position shown in Fig. 7, it will indicate that the adjusting-rod and vise-jaw are positioned for the casting of lines of which the length is an odd number of half-picas or nonpareils. Thus, by glancing at the handle 29, the operator of the type-casting machine may be assured at any time that the vise-jaw adjusting-rod is locked in its adjustment, and that the adjustment is for line-lengths of full picas, or for the intermediate lengths usually denoted as nonpareil lengths, as the case may be.

Now, having described my invention, what I claim and desire to secure by Letters Patent is:

1. In a structure of the class described, the combination with a transversely grooved adjusting-rod, and a block having a longitudinal opening through which said rod extends slidably, of a locking-pin extending slidably through a transverse opening in said block, said transverse opening intersecting the longitudinal opening for the adjusting-rod, and said locking-pin having an elongated opening through which the adjusting-rod passes, there being series of teeth at the opposite ends of said opening in the locking-pin, said series of teeth being alternatively engageable in the grooves of the adjusting-rod by movement of the locking-pin relative to said block, one series of said teeth being interspaced relative to the other series whereby to engage in the grooves of the rod when the same is at positions intermediate the positions at which the grooves are engaged by the teeth of the other series, and means for actuating said locking-pin.

2. In a structure of the class described, the combination with an adjusting-rod having a uniform series of transversely extending grooves therein, and a block through which said rod extends slidably, of a locking-pin extending through said block transversely of the opening for the adjusting-rod and movable laterally of the adjusting-rod axis, members carried by said locking-pin and engageable in the grooves of the adjusting-rod to present longitudinal movement of said rod relative to the block, other members carried by said locking-pin and engageable in the grooves of the adjusting-rod alternatively with the first-named members, said second-named members being interspaced relative to the first-named members in a direction longitudinal of the adjusting-rod, and means for actuating the locking-pin to selectively engage said members with the rod and to retain the same in engaged position.

3. In a structure of the class described, the combination with an adjusting-rod having a series of laterally extending portions uniformly spaced longitudinally thereof, and a

- block through which said rod is longitudinally movable, of a locking-member mounted in said block in fixed relation thereto longitudinally of the adjusting-rod and movable relatively thereto laterally of the adjusting-rod, said locking-member having a plurality of elements severally engageable with the laterally extending portions of the adjusting-rod to lock the rod in adjusted relations to the block, said elements being relatively interspaced longitudinally of the adjusting-rod, and means for actuating said locking-member to engage said several elements with the rod selectively.
4. In a structure of the class described, the combination with an adjusting-rod having a series of laterally extending portions uniformly spaced longitudinally thereof, and a block through which said rod is longitudinally movable, of a locking-member mounted in said block in fixed relation thereto longitudinally of the adjusting-rod and movable relatively thereto laterally of the adjusting-rod, and elements carried by said locking-member at opposite sides of the adjusting-rod and alternately engageable with the laterally extending portions of the adjusting-rod to lock the rod in fixed relations to the block.
5. In a structure as set forth in claim 4, means connecting said block and locking-member and movable to actuate said locking-member to its alternative locking positions, and means for retaining said actuating means in the alternative locking positions.
6. In a structure as set forth in claim 4, means connecting said block and locking-member and movable to actuate said locking-member alternatively to selected locking positions, said means being immovable from said locking positions thereof by force exerted thereon from the locking-member.
7. In a structure of the class described, the combination with the vise-jaw adjusting-rod, wedge-block, and locking-pin movable in the wedge-block transversely of the adjusting-rod to engage and lock the latter in adjusted relations to the wedge-block; of actuating means for said locking-pin comprising a crank-disk mounted to revolve on an axis fixed relatively to the wedge-block, a crank-pin carried by said disk and operatively connected with the locking-pin, and a handle for turning said crank-disk and indicating the position of the locking-pin.
8. In a structure of the class described, the combination with the vise-jaw adjusting-rod, wedge-block, and locking-pin movable in the wedge-block transversely of the adjusting-rod to engage and lock the latter in adjusted relations to the wedge-block; of a crank-disk mounted to revolve on an axis fixed relatively to the wedge-block, a crank-pin carried by said disk and operatively connected with the locking-pin, a handle connected with said

crank-disk for turning the same, and frictional braking means tending to retain the crank-disk in positions to which it is turned.

9. In a structure of the class described, the combination with the vise-jaw adjusting-rod, wedge-block and locking-pin movable in the wedge-block transversely of the adjusting-rod to engage and lock the latter in adjusted relations to the wedge-block; of a crank-member operatively connected with the locking-pin and having a throw normally greater than the travel of the locking-pin, actuating means connected yieldingly with said crank-member, and stops for limiting movement of said actuating means.

10. In a structure of the class described, the combination with the vise-jaw adjusting-rod, wedge-block, and locking-pin movable in the wedge-block transversely of the adjusting-rod to engage and lock the latter in adjusted relations to the wedge-block; of means for actuating said locking-pin and retaining the same in selected positions, comprising a crank-disk mounted for rotation about an axis fixed relatively to the wedge-block, a crank-pin mounted upon said disk for movement radially thereof and operatively connected with the locking-pin, resilient means yieldingly holding said crank-pin at a radius greater than required for effecting a maximum travel of the locking-pin, a handle secured to the crank-disk, and stops arranged to prevent movement of the crank-disk in excess of predetermined amounts past the dead-center positions of the crank-pin.

11. A structure as set forth in claim 10, including a block slideable radially of the crank-disk and carrying the crank-pin, said block being engaged by the resilient means and normally held thereby in frictional engagement with a braking surface to resist rotation of the crank-disk.
